UNITED STATES PATENT OFFICE.

GEORGE BERNERT AND JACOB BERNERT, OF SOUTH GERMANTOWN, WISCONSIN.

PNEUMATIC ELEVATOR.

1,002,556.

Specification of Letters Patent.

Patented Sept. 5, 1911.

Application filed December 6, 1910. Serial No. 595,922.

To all whom it may concern:

Be it known that we, GEORGE BERNERT and JACOB BERNERT, both citizens of the United States, and residents of South Germantown, in the county of Washington and State of Wisconsin, have invented certain new and useful Improvements in Pneumatic Elevators; and we do hereby declare that the following is a full, clear, and exact description thereof.

Our invention has for its primary object to provide simple, economical and effective elevators, the invention being particularly applicable to pneumatic elevators such as shown and described by us in our application for patent filed May 13, 1910, Serial No. 561,201, the construction and arrangement of which elevator is such that the product to be elevated is delivered to an air blast tube through a valve-controlled branch in such manner that the air blast from a fan is not interrupted or broken incidental to opening of the valve, whereby the product is discharged into said air blast tube or conveyer trunk at a predetermined distance from the fan.

Specific objects of our invention are to provide a simple and effective valve mechanism; to provide an auxiliary mechanical elevator whereby the product is delivered from a lower plane to a hopper communicating with the conveyer trunk; to provide means for adjusting such mechanical elevators to various elevations with respect to their receiving end, and to provide a simple, economical gear connection between the mechanical elevator and fan.

With the above objects in view our invention consists in certain peculiarities of construction and combination of parts as set forth hereinafter with reference to the accompanying drawings and subsequently claimed.

In the drawings Figure 1 represents a sectional elevation of a portion of an elevator embodying the features of our invention, the section being indicated by line 1—1 of Fig. 2; Fig. 2, a detail transverse section of the same as indicated by line 2—2 of Fig. 1; Fig. 3, a plan view of the same; Fig. 4, a detail section illustrating a form of valve mechanism, the section being indicated by line 4—4 of Fig. 2; Fig. 5, a side elevation of an elevator embodying the features of our invention provided with an inclined receiving elevator section, the mouth of which

is below the plane of the conveyer trunk, the elevator being illustrated as applied to a threshing machine with the mechanical elevator section arranged to receive grain from a discharge of said machine; Fig. 6, an enlarged detail sectional elevation of a portion of the conveyer trunk and its valve-controlled grain receiving aperture, together with a portion of the mechanically operated delivery elevator section, and Fig. 7, a sectional view of the same upon line 7—7 of Fig. 6.

Referring by characters to the drawings, 1 represents a fan casing provided with a discharge trunk 2 and a fan shaft 3. The discharge trunk has a grain receiving aperture 4 therein, about which is fitted a box 5 that is secured about the aperture. Secured to the mouth of the box is a transversely disposed tubular trough 6 having mounted therein a spiral conveyer 7, the shaft 8 of which is journaled in boxes 9, 10, respectively, with which the end of the trough is provided. The conveyer flight terminates at a point approximately alined with the inner edge of the trunk aperture, the shaft at this point being provided with a collar against which is abutted a circular valve 12 that is loosely mounted upon the shaft, there being a coiled spring 13 surrounding the shaft and interposed between the valve and inner shoulder of the bearing 9, which bearing is provided with an internal recess for the reception of an extension of said spring.

By utilizing a valve of the above mentioned construction, it will be seen that rotation of the spiral conveyer carrying grain or other product would cause said grain to force the valve 12 in opposition to the spring from its seat, thereby opening communication to the trunk below through the aperture 4, whereby grain is delivered to said trunk, the valve being automatically closed or opened with relation to the flow of grain therein.

The outer end of the conveyer trough 6 is suitably supported by a pillar 14, the upturned mouth of which conveyer forms an open hopper 15, through which grain is delivered to the conveyer. Journaled in boxes 16, that are secured to the hopper 15 is a counter-shaft 16 that carries a pulley 17, which is in belt connection with a pulley 18 that is mounted upon the fan shaft, whereby power is applied to said counter-shaft, it being understood that, while we have shown

a single set of pulleys, that the same may be provided with a series of stepped faces for varying the speed of the counter-shaft. The opposite end of the counter-shaft is in 5 pulley and belt connection with the conveyer-shaft 8, whereby the same is rotated.

One wall of the hopper 15 is provided with a recess 15^a, through which recess the discharge end of a conveyer trough 19 projects, the trough being cut away to form a mouth 19^a through which grain is delivered to the hopper. The trough 19 is pivotally hung about the counter-shaft through brackets 20 that extend from said trough and are 15 provided with apertures into which the boxes 16 extend. Thus it will be seen that the trough 19 may be adjusted about the axes of the counter-shaft.

The receiving end of trough 19 terminates 20 with an open hopper 21 through which grain is discharged, the trough being provided with a spiral conveyer 22, its shaft 23 being journaled in bearings at the opposite ends of said trough. The spiral conveyer 22 is 25 driven from the counter-shaft 16 by a bevel gear 24 that meshes with a corresponding bevel gear 24^a, which bevel gear is secured to shaft 23 of said spiral conveyer. An apron 25 is hinged to the trough 19 adjacent to one edge of its mouth 19^b, the apron, as shown in Fig. 1, being suspended by gravity in juxtaposition to the adjacent side-wall of the hopper 15. When the outer 30 end of the conveyer trough 19 is elevated 35 for the purpose of adjustment with relation to grain to be delivered thereto, the mouth 19^b of the trough would describe an arc of a circle with relation to the axis of counter-shaft 16 and, in order to prevent grain that 40 is discharged from said mouth from dropping outside of the hopper 15, this apron is provided, it being adapted to bridge the space between the mouth and bottom of the recess 15^a in the hopper.

45 From the foregoing description it will be understood that the conveyer section 22 may be of any desired length, rendering it possible to elevate grain mechanically at various elevations below the plane of the conveyer trough 2, or above said plane by suitable adjustment. Thus said trough constitutes a mechanical loading conveyer in conjunction with the receiving hopper 15 of the conveyer mechanism.

50 As shown in Fig. 5, the elevator mechanism is mounted upon a separator or threshing machine A, from which machine the fan is adapted to receive its power by belt connection not shown. In this instance it is desirable to receive the elevated and cleaned grain from the weigher or bagger B of the machine, the discharge mouth of which bagger is below the plane of the trunk 2. To provide means for delivering grain 60

from the bagger to the pneumatic elevator

trunk 2, we have illustrated a trough section 19^a of a loading conveyer having its open mouth hopper 21^a directly under the bagger discharge, the trough section 19^a being disposed at an angle thereto and inclined upwardly to a point above the pneumatic elevator trunk 2. From this point the trough section 19^a is formed with an abrupt downwardly inclined angular discharge section 26. A shaft 27 of a spiral conveyer that is rotatable in the trough section 19^a extends beyond the intersecting joint between said trough section and opposite inclined section 26, the shaft being in miter-gear connection with a counter-shaft 16^b, which is journaled in bearings of brackets 28 carried by the aforesaid trough. The counter-shaft is driven by a belt and pulley connection with the fan shaft 3. Grain is delivered to the discharge trough section 26 and by gravity discharged to the valve-controlled aperture 4 of the trunk 2, the pivoted flap-valve 12^a of which is normally held closed by a spiral spring 29 that encircles a rod 29^a, which rod is in pivotal connection with the valve and projects through an aperture in the wall of the discharge trough section 26, there being a bracket 30 secured to said section, between which, and an adjusting nut 31 that is carried by the rod, the spring is interposed. By this arrangement resistance of the valve to open in opposition to weight of the grain is adjusted.

In the mechanism just described, the conveyer trough 19^a, is rigidly secured to the elevator air trunk, but it will be understood that the same may be adjustable as to inclination in the same manner as shown in connection with the conveyer trough 19, illustrated in Fig. 1.

In the operation of the device as shown in Fig. 5, the grain, after entering the trunk 2, is, by the pneumatic force, discharged through said trunk to the point of delivery irrespective of its length or inclination.

We claim:

1. A pneumatic elevator comprising a fan-casing having an apertured air discharge trunk extending therefrom, a fan shaft journaled in the casing, a spring-controlled valve mounted above the trunk aperture, a trough section in communication with the valve and inclosing the same, an inclined trough in communication with the trough section having an open hopper receiving end, a spiral conveyer mounted within the inclined trough section, a counter-shaft, a miter-gear connection between the spiral conveyer shaft and counter-shaft, and a pulley and belt connection between the counter-shaft and fan shaft.

2. A pneumatic elevator comprising a fan-casing having an apertured air discharge trunk extending therefrom a fan shaft mounted in the casing a valve box

cured to the discharge trunk above its aperture, a spring-controlled flap-valve mounted within the box, a transversely disposed trough in communication with the trunk aperture and incasing its valve, a spiral conveyer mounted in the transverse trough, a vertical hopper extending from the trough, boxes secured to the hopper, a counter-shaft journaled in the boxes, a second trough having arms journaled upon the boxes, the trough being provided with a discharge opening that communicates with the hopper and having a receiving hopper at its opposite end, a spiral conveyer mounted 10 in the trough, a miter-gear connection between the spiral conveyer and counter-shaft, a driving belt and pulley connection between the counter-shaft and fan-shaft, and a second driving belt and pulley connection 15 between the counter-shaft and shaft of the spiral conveyer mounted in the transverse trough.

3. In a pneumatic elevator having an apertured discharge trunk, a spring-con-

trolled valve for the aperture, and a hopper 25 communicating with the valve-controlled aperture; the combination of a counter-shaft journaled in boxes carried by the hopper, a trough having arms journaled about the counter-shaft, the trough being 30 provided with a discharge aperture that communicates with the hopper and an open receiving hopper at its opposite end, a shaft having spiral flights mounted in the hopper, a miter-gear connection between the last 35 named shaft and journal-shaft, and means for driving said counter-shaft.

In testimony that we claim the foregoing we have hereunto set our hands at Menomonee Falls in the county of Waukesha and 40 State of Wisconsin in the presence of two witnesses.

GEORGE BERNERT.
